EDWARD T. BOSTROM, OF NEWNAN, GEORGIA.

Letters Patent No. 70,947, dated November 19, 1867; antedated November 8, 1867.

IMPROVED PADDLE-WHEEL.

The Schedule referred to in these Letters Patent and making part of the same.

TO ALL WHOM IT MAY CONCERN:

Be it known that I, E. T. BOSTROM, of Newnan, in the county of Coweta, and State of Georgia, have invented a new and improved Paddle-Wheel; and I do hereby declare that the following is a full, clear, and exact description thereof, which will enable those skilled in the art to make and use the same, reference being had to the accompanying drawings, forming part of this specification.

This invention relates to a new and improved paddle-wheel designed for both river and sea steamers, and has for its object a more efficient action than hitherto of the buckets or float-boards against the water, and the perfect operation of the buckets or float-boards at varying depths of immersion. The ordinary paddle-wheels, provided with fixed radial buckets or float-boards, have a very imperfect action in the water during a certain portion of their movement therein, and in order to obtain the greatest effect or maximum propelling power, a certain depth of immersion is necessary. This cannot always be obtained, as the depth of immersion will vary according as the vessel is more or less heavily laden, and besides, in sea steamers, the rolling of the same causes the buckets or float-boards to be at one moment deeply immersed and at the next quite near the surface of the water. This difficulty attending the operation of the ordinary paddle-wheels, it is believed is fully obviated by my invention.

Figure 1 is a side sectional view of my invention, taken in the line $x x$, fig. 2, and

Figure 2 a plan or top view of the same.

A represents the shaft of the wheel; B, the arms attached radially to the shaft in any proper manner; and C represents rotary buckets or float-boards, which are constructed and arranged as follows: Between the outer parts of the arms B there are secured shafts, D, which are allowed to rotate freely, and have radial arms, a, attached, to which the buckets or float-boards C are secured. In the drawings, each shaft D is represented with four buckets or float-boards attached, but more may be employed if necessary. Two sets of arms, B, of four each, are also shown, but more may be used, and also more of the sets of buckets or float-boards, according to the size or diameter of the wheel. The sets of buckets or float-boards are allowed to turn freely in order that they may adjust themselves while passing through the water, as follows: Let $y y$ represent the water line or surface of the water, and the arrow 1 indicates the direction in which the wheel rotates; 1 2 two sets of buckets or float-boards at the surface of the water, at opposite sides of the wheel-shaft, and 3 a set at the deepest point of immersion, or directly underneath the wheel-shaft, as shown in fig. 1. The sets of buckets 1 on entering the water will assume the position shown in fig. 1, but as they proceed downward in a curvilinear direction, and the whole set becomes fully immersed, the bucket 1¹, in consequence of describing the longer curve, will be moved upward or outward until buckets 1¹ 1² will be in a horizontal plane, as indicated by the red solid lines in fig. 1, the red dotted lines corresponding to the original portion of the buckets as they entered the water. The other two buckets 1³ 1⁴ will of course be in a vertical plane, and these latter buckets will of course have the greater propelling power, as they present a greater area to the water in the direction of the path of the rotation of the wheel. The difference, therefore, between my wheel and the ordinary ones with fixed buckets is obvious, as the latter have the position indicated by the dotted lines 5 and 6, where the efficient buckets of my improvement have the position indicated by 1³ 1⁴. As the buckets reach the point underneath the shaft of the wheel, the buckets 1² 1³ have the greater propelling effect, the buckets 1¹ 1⁴ having the lesser propelling effect, the latter buckets deriving their efficiency from the falling of the water into the vacuum between 1² and 1⁴ and the rushing up of the water between 1³ and 1¹. In this position, 3, of the buckets, no advantage is obtained over the ordinary fixed radial buckets, and when they reach an intermediate position between 3 and 2, their position is the same as shown at 1, but from the latter point to 2 the set of buckets turns, and 1¹ and 1² assume the position that 1³ 1⁴ occupied at point 3. This wheel is as simple in construction as the ordinary wheel with fixed buckets, is not more liable to get out of repair, and can be used upon any wheel of that construction, and a full set can be stowed away in some corner, and, if needed, may be attached as quickly as the common flat bucket. Its greatest propelling power will be with the main shaft at the water line. In striking drift logs or ice, if it does not roll upon and sink them, the buckets will turn upon their axes and thereby cushion the blow and protect the wheel from injury. If hung upon an even keel, it will "walk" directly over sand-bars. If necessary or desired, two of the buckets in each set may be loaded in order to insure their entrance into the water, as indicated in fig. 1.

Having thus described my invention, I claim as new, and desire to secure by Letters Patent—

The construction of four buckets, C, upon the revolving shaft D, arranged upon the ends of the radial revolving arms B, substantially as described for the purpose specified.

EDWARD T. BOSTROM.
